UNITED STATES PATENT OFFICE.

CHARLES M. MOGNI, OF NEW YORK, N. Y.

STRIPPING MACHINE.

Application filed April 22, 1921. Serial No. 463,689.

To all whom it may concern:

Be it known that I, CHARLES M. MOGNI, a citizen of the United States, and resident of the city of New York, borough of Manhattan, county of New York, and State of New York, have invented a new and Improved Stripping Machine, of which the following is a full, clear, and exact description.

My invention relates to a stripping machine, and an article of manufacture which is capable of being produced by this machine.

It is a well appreciated fact, in connection with brushes, that it has been necessary to employ a brush back, suitable members constituting bristles, and means for retaining the bristles in applied position with respect to the back. Considerable objection has arisen, more particularly with the latter means, in that the bristles were liable to become loosened.

With this in view, a number of manufacturers have vulcanized or cemented the bristles to the back, which has overcome this difficulty to a great extent.

Further, the cost of manufacturing this latter type of brush, has been such that the construction has been inapplicable to brushes intended for ordinary uses, such as scrubbing, etc., in that the retail price of the same would not be proportionate to the value of the article.

With this in mind, my present invention aims to provide a stripping machine which will be capable of producing such articles as brushes of any type, which shall incorporate the advantage of having their bristle elements virtually incapable of becoming accidentally removed from the member constituting the back of the same.

A further object of this invention is the construction of a stripping machine, as well as the article of manufacture produced thereby, which machine will be practically automatic in operation, aside from the fact that it will be extremely simple in construction, and capable of being manufactured at a nominal figure.

Further objects of my invention will appear in the annexed specification and drawings, which latter illustrate one practical embodiment thereof, and in which:

Figure 1 is a side view of a machine embodying my improved construction.

Figure 2 is a sectional view taken along

the lines 2—2 and in the direction of the arrows indicated in Figure 1.

Figure 3 is an enlarged sectional view of one of the frames utilized.

Figure 4 is a detail thereof.

Figure 5 illustrates the stripping element employed.

Figure 6 is a sectional view taken through the finished article produced by the machine, and

Figure 7 is a partly fragmentary plan view of one of the elements permitting of the semi-automatic operation of the machine.

Referring now more particularly to Figures 1 and 2 it will be seen that the reference numeral 10 indicates a base of any suitable construction which constitutes a rigid support for the machine, and to which a frame 11 is secured.

Mounted within the frame 11, and more particularly the longitudinally centrally extending members 12 thereof, is a stripping plate 13 which is slidably retained in this position by any suitable means, such as that of having its outer edges attached to apex members co-operating with a corresponding groove in the inner faces of the longitudinal members 12.

The stripping plate preferably has a pair of backing sheets 14 secured to its side faces, and these sheets retain teeth 15 in applied position upon the plate 13, and with a view of reciprocating the entire stripping element thus provided, it will be noted that I employ any suitable means such as a rotatable crank 16 having one of the ends of a pitman 17 secured to it, the opposite end thereof being rockingly attached as at 18, to the stripping plate 13 thus permitting of the stripping element being moved longitudinal of the frame 11 upon the crank being rotated by means of the pulley 19.

Guide rails 20 are transversely mounted within the frame 11, and these guide rails serve to mount slidably arranged trays 21 positioned one to each side of the stripping member aforescribed. Also, oppositely screw threaded bars 22 extend transversely of the frame 11, and these bars project through correspondingly threaded openings in lugs 23 forming a part of each of the trays 21 so that upon the bars 22 being rotated by any suitable means such as worms 24 forming parts of shafts 25, it will

2
be obvious that the trays 21 will either be fed away from or towards the stripping member.

With a view now of providing means which will serve to permit of the elements to be operated upon being mounted within the trays, I employ clamping racks 26 each comprising a plurality of longitudinally extending spaced parallel bars 27 secured together by means of transversely extending bars 28 which latter have their outer ends screw threaded to permit of screw threaded sleeve 29 being mounted thereon, which sleeves may be rotated by means of handles 30 thus obviously varying the spaces between the bars 27.

Each of the trays 21 are formed with slots 31 in certain of their side edges, and adjacent the inner ends of these slots, 20 spring pressed latches 32 are slidably mounted. The clamping racks each carry pins 33 capable of being accommodated within the slots 31, and sleeve lugs 34 are also secured to their lower edges and co- 25 operate with openings in the lower portions of the trays 31 so that the clamping rack may be swung, and are retained in applied position with respect to the tray 21, with 30 which it is associated, it being also obvious that the pins 33 will move into the slots 31, and be retained in their proper position by means of the latch 32 so that one tray and clamping rack constitute in assembled position, a single unit.

35 Although my invention is not necessarily limited to use in this connection, it is primarily adapted to act upon blocks, sawed or otherwise formed from the trunk of a palmetto palm. The trunk of these trees, as is well known, consists of a mass of fibres, 40 which embody great resistance qualities, the spaces between the fibres being completely filled by a mass of fine particles in intimate contact with the fibres. In use, the clamping rack is primarily removed from the tray by retracting the latch 32, and in swinging the clamping arm outwardly, and subsequently lifting the same from the tray. A rotation of the sleeves 29 will permit of the 45 bars 27 being spaced to the necessary extent, to allow of the blocks specified being arranged between their side faces. Subsequent to this a clamping of the bars by means of these sleeves may be effected, and 50 obviously any movement on the part of the blocks will be prevented.

The clamping racks are now re-applied to their respective trays and the machine is then ready for operation.

55 With a view of providing means which will not alone serve to rotate the shafts 25 synchronously, but which will also permit of a semi-automatic operation of the entire device, it will be noted reference being had to Figure 1 that the pulley shaft serves to

drive a supplemental shaft 35 by means of beveled gears 36. A clutch sleeve 37 is slidably keyed to the shaft 35, and may engage clutches affixed to either the loosely mounted gear 38 or a similarly mounted gear 39, both 70 arranged upon the supplemental shaft 35, it being noted that these gears are constantly in mesh with a gear 40 fixedly secured to one of the shafts 25, the second shaft 25 being driven from the first shaft by any suitable drive such as a chain 41.

Thus a rotation of the pulley 19 will result in the arrangement illustrated in Figure 1, primarily in the stripping element being reciprocated by means of the pitman 17. 80 Consequently the supplemental shaft 35 will also drive the clutch sleeve 37, which, meshing with the clutch of the gear 39 will impart rotation to both of the shafts 25, and through the worms 24 to the bars 22, this 85 resulting in a feeding of the trays towards a central point.

Obviously the teeth 15 will gradually move to a greater depth into the blocks 42, and will remove the mass of fine material 90 from between the fibres thereof without in the slightest injuring the latter. Obviously this stripping of the mass from between the fibres must cease at a point well in advance of the rear face of the blocks, and with a 95 view of automatically permitting of this function being accomplished, it will be seen, reference being had to Figures 1 and 7, that one of the trays 21 carries a lug 43 which co-operating with a shifting fork 44 controlling a series of linkage 45, will obviously result in this linkage being positively moved upon the tray 21 moving to either of its extreme positions. A bell crank 46 is secured to the outermost end of the linkage 45, and 100 is rockingly mounted upon the base 10, said 105 rocking being preferably limited by means of stops 47, it being also noted that the inner end of the bell crank is secured to the clutch sleeve 37.

110 Thus upon the trays 21 having been fed in for a certain predetermined distance, permitting of the mass of fine material being removed from the fibres of the blocks 42 to a desirable depth, the lug 43 will co-operate 115 with the inner arm of the fork 44 and move the linkage 45, thus shifting the clutch sleeve 37, this latter movement being preferably accelerated by means of a weight 48 affixed to the outer arm of the bell crank 46.

120 Assuming that through negligence, the machine was not stopped after a mass of material had been removed from between the fibres of the blocks, it will thus be seen that no harm might result, in that the trays 125 would continue to be fed outwardly, and inwardly until such time as the machine was brought to a stop, the stripping action always terminating at a predetermined depth.

- Thus it will be seen that the objects set forth in the preamble of this specification have been accomplished, in that a stripping machine of extremely simple construction, and efficient operation is primarily provided. Furthermore, brushes thus constructed will be found to include one integral element provided by nature in that both the fibres and the mass of fine material retained and constituting a backing plate, and securing element for the fibres form a single part of the trunk, the fibres constituting the bristles being merely produced by removing the mass of fine material to a predetermined depth.
- Also it has been found that brushes constructed in this manner are not alone limited to use such as scrubbing etc. but that portions of the blocks constituting the backing plates may be polished and finished to an extent to produce an extremely pleasing article, susceptible to being used in any association, it being also noted, in this connection that this article is capable of being produced at an extremely nominal figure.
- Obviously numerous modifications of structure might readily be resorted to without in the least departing from the spirit of my invention, which I claim as:
1. A stripping machine, including a frame, trays movably mounted within said frame, a stripping element also movably mounted within said frame, and means for feeding said trays directly towards said stripping element.
2. A stripping machine, including a frame, a tray movably mounted within said frame, a stripping element also movably mounted within said frame, means for feeding said tray directly towards said stripping element, and automatically retracting the same after said trays have been moved towards said stripping element for a predetermined distance.
3. A stripping machine, including a frame, trays mounted for reciprocation within said frame, a stripping element movably mounted within said frame, and common means for moving said trays and stripping element.
4. A stripping machine, including a frame, trays movably mounted within said frame, a stripping element reciprocatingly mounted within said frame, common means for moving said trays and stripping element, said stripping element moving in a path transverse to the direction of movement of said trays.
5. A stripping machine including a frame, a stripping element slidably mounted within said frame and movable longitudinally thereof, trays arranged within said frame and movable transversely thereof, and means connected to said stripping element and trays for moving the same in the direction specified.
6. A stripping machine, including a frame, a stripping element movably mounted within said frame, trays also movably mounted within said frame, means for moving said stripping element and trays, and clamping racks detachably secured to said trays.
7. A stripping machine including a frame, a stripping element movably mounted within said frame, trays also movably mounted within said frame, means for moving said stripping element, clamping racks detachably secured to said trays, said clamping racks comprising a number of spaced parallel bars movable with respect to each other, and means co-operating with said bars for moving the same towards each other.
8. A stripping machine including a frame, a stripping element movably mounted within said frame, trays also movably mounted within said frame, means for moving said stripping element, clamping racks detachably secured to said trays, said clamping racks comprising a number of spaced parallel bars movable with respect to each other, further bars extending transversely through said first named bars and being formed with screw threads adjacent their outer ends, and sleeves mounted within said screw threads and engaging the outermost of said bars.
9. A stripping machine, including a frame, trays transversely movable to said frame, a stripping member longitudinally movable within said frame and arranged between said trays, a crank shaft, a pitman connecting said stripping member to said crank shaft, further shafts driven by said crank shaft, and oppositely screw threaded rods extending transversely of said frame, and being connected to said trays and means connecting said rods with said further shafts.
10. A stripping machine, including a frame, trays transversely movable to said frame, a stripping member longitudinally movable within said frame and arranged between said trays, a crank shaft, a pitman connecting said stripping member to said crank shaft, further shafts driven by said crank shaft, and oppositely screw threaded rods extending transversely of said frame, means connected to said trays and engaging said rods, means connecting said rods with said last named shafts, a selective gearing interposed between said crank shaft and last named shafts, and a clutch adapted to engage certain of said gearing.
11. A stripping machine including a frame, trays transversely movable to said frame, a stripping member longitudinally movable within said frame and arranged between said trays, a crank shaft, a pitman connecting said stripping member to said crank shaft, further shafts driven by said crank shaft, and oppositely screw threaded rods extending transversely of said frame, means

connected to said trays and engaging said rods, means connecting said rods with said last named shafts, a forward and reversing gearing interposed between said crank shaft and last named shafts, a clutch adapted to engage one of said gears, and means for automatically shifting said clutch.

12. A stripping machine including a frame, a tray and a reciprocable stripping element

movable with respect to said tray and in a direction parallel to the body of the same.

13. A stripping machine including a frame, a tray and a reciprocable stripping element, said tray and stripping element being movable with respect to each other in a plane substantially parallel to each of their bodies.

CHARLES M. MOGNI.
